WRITING INSTRUMENT HOLDER

John W. Fitz Gerald, Milwaukee, Wis., assignor
to Briggs & Stratton Corporation, Milwaukee,
Wis., a corporation of Delaware

Application July 15, 1931. Serial No. 550,865

6 Claims. (Cl. 120—108)

This invention relates to certain new and useful improvements in writing instrument holders, and refers more particularly to holders for pens and pencils, and known in the art as pen desk sets.

5 In conventional desk sets heretofore in use, the receptacle for the pen or other writing instrument was usually supported from a base by a ball and socket connection, the sphere or ball member being attached to the receptacle. Substantially universal movement of the receptacle with respect to the base was thus obtained, but practically the entire spherical surface of the ball, including those portions exposed to view, were subjected to wear during the various movements 15 of the receptacle.

In view of this condition, it was impractical to plate the ball member, for the plating soon wore off and resulted in an unsightly appearance. It was, therefore, necessary to make the ball 20 member of solid metal and as gold or similar metal was usually used, the increased cost entailed thereby was appreciable.

It is, therefore, an object of this invention to provide a novel mounting for the ball member 25 whereby the wear on the ball member takes place only at concealed portions, and thus makes plating feasible.

Another object of this invention is to simplify the design and reduce the number of parts comprising the mounting for the receptacle.

With the above and other objects in view which will appear as the description proceeds, the invention resides in the novel construction, combination and arrangement of parts substantially 35 as hereinafter defined by the appended claims, it being understood that such changes in the precise embodiment of the herein disclosed invention may be made as come within the scope of the claims.

40 In the accompanying drawing, is illustrated one complete example of the physical embodiment of the invention constructed according to the best mode so far devised for the practical application of the principles thereof, and in which:

45 Figure 1 is a fragmentary view of a pen desk set embodying this invention, with parts in section and parts in elevation;

Figure 2 is a cross section view taken through Fig. 1 on the plane of the line 2—2; and

50 Figure 3 is a perspective view of the elements of the receptacle mounting shown separated and in their proper order of assembly.

Referring now more particularly to the accompanying drawing in which like numerals indicate 55 like parts throughout the several views, the numeral 5 represents the base of a pen desk set having a bore 6 whose lower end communicates with an enlarged recess or pocket 7 formed in the bottom of the base. The upper end of the bore 60 is flared outwardly or taperingly enlarged, as at 8.

Inserted into the bore 6 is the stem portion 9 of a mounting structure 10 by which a writing instrument receptacle 11 is swivelly mounted from the base 5. The receptacle 11, as is customary in articles of this type, has a bore, not shown, opening to its outer end into which the pen or other writing instrument is inserted.

65 The mounting structure 10 comprises a disc 12 fixed to the inner end of the receptacle 11, as at 13, and two substantially hemi-spherical members 14 having downward extensions 15 which together form the stem 9. The inner faces of the members 14 have cylindrical recesses or pockets 16 which are adapted to receive correspondingly shaped and sized lugs or projections 17 formed on the opposite faces of the disc 12 so that when the hemi-spherical members 14 are assembled with the disc 12, the disc 12 and consequently the receptacle 11 carried thereby, is mounted for pivotal movement about the transverse axis of the 70 members 14.

75 The disc 12 is of such thickness that when assembled with the members 14, a perfect sphere is formed and when the extensions 15 forming the stem 9 are inserted into the bore 6 of the base, 80 the sphere afforded by the assembled members 14 and the disc 12, engages the outer portion of the taperingly enlarged outer end 8 of the bore 6 to mount the sphere for rotation about the axis of the bore 6.

85 It is observed that the innermost ends of the extensions 15, which form the stem, are provided with flanges 18. These flanges engage behind the edges of an opening 19 formed in a bowed leaf spring 20, the ends of which engage the bottom of the recess 7 to yieldably draw the stem 9 and consequently the entire mounting structure down into the bore so as to maintain the same 90 assembled with the base.

95 To assemble the extensions 15 with the spring 20, it is only necessary to force the middle portion of the spring 20 upwardly and engage the inner ends of the extensions 15 in its opening 19 and then position the disc 12 between the members 14.

100 As hereinbefore noted, the disc 12 mounts the receptacle 11 for pivotal movement about the transverse axis of the sphere, and inasmuch as the entire mounting structure 10 is rotatable about the axis of the bore 6, the receptacle 11 has substantially a universal movement with respect 105 to the base. The members 14 and the disc 12 may be plated to enhance the appearance of the device, and inasmuch as the members 14 are mounted only for turning movement about a fixed axis, and inasmuch as these members engage only the 110 outer end of the tapered bore 8, any possible wear on the plating of these members takes place at concealed portions, and to preclude rubbing of the plating from the peripheral edge of the disc 12, the disc 12 is slightly smaller in diameter than 115 120

the sphere so that the peripheral edge of the disc never comes in contact with the tapered bore 8.

From the foregoing description taken in connection with the accompanying drawing, it will be readily apparent to one skilled in the art to which an invention of the character described appertains that this invention provides an extremely simple and efficient manner of mounting the receptacle of a pen desk set from its base whereby substantially universal movement is accommodated, that the mounting structure is composed of a minimum number of parts, and that any possible wear on the mounting structure takes place at concealed portions, so that it is feasible to plate the elements thereof and effect a reduction in the cost of manufacture.

What I claim as my invention is:

1. In a writing instrument holder of the character described, a base having a bore, and a writing instrument receptacle, means for mounting the receptacle from the base for substantially universal movement and comprising a disc carried by the receptacle, a pair of substantially hemispherical members disposed one on each side of the disc and together with the disc forming substantially a sphere, means on said disc for pivotally connecting said members with said disc, said sphere being of a diameter greater than the diameter of the bore in the base and seated on the outer peripheral edge of said bore, and spring means engaging diametrically extending foot portions of said hemispherical members for holding the sphere in its position resting on the outer peripheral edge of the bore while permitting rotation of the sphere about the axis of the bore, the diameter of the disc being less than the diameter of the sphere whereby the peripheral edge surface of the disc is precluded from contacting with the outer peripheral edge of the bore.

2. In a writing instrument holder of the character described, including a base having a bore and a writing instrument receptacle, means for mounting the receptacle for substantially universal movement with respect to the base and comprising a disc connected with the receptacle, a pair of substantially hemispherical members one on each side of the disc and together with the disc forming substantially a sphere of a diameter greater than the diameter of the bore and seated on the outer peripheral edge portion of the bore, a pivotal connection between the hemispherical members and the disc enabling pivotal movement of the receptacle about an axis angular to the axis of the bore, extensions on the hemispherical members extended into the bore, and spring means connected with said projections and engaging a portion of the base to hold the sphere in its position seated on the peripheral edge portion of the bore while enabling rotation of the sphere about the axis of the bore.

3. In a writing instrument holder of the character described, including a base having a bore, and a writing instrument receptacle, means for mounting the receptacle for substantially universal movement with respect to the base and comprising a disc connected with the receptacle, a pair of substantially hemispherical members one on each side of the disc and together with the disc forming substantially a sphere of a di-

ameter greater than the diameter of the bore and seated on the outer peripheral edge portion of the bore, a pivotal connection between the hemispherical members and the disc enabling pivotal movement of the receptacle about an axis angular to the axis of the bore, extensions on the hemispherical members extended into the bore, a flat spring member having an aperture in which the end portions of the extensions are received, abutments on the extremities of said extensions engaged behind the edge of the aperture in the flat spring to readily detachably connect said extensions with the flat spring and said flat spring engaging part of the base to urge the extensions and consequently the sphere into the bore whereby the sphere is retained in its seated position and rotation thereof about the axis of the bore is permitted.

4. In a device of the character described, a base having a cylindrical bore and a flared portion in the upper end of said bore, a writing instrument receptacle and means to mount said receptacle on said base comprising a disc carried by said receptacle having a cylindrical projection extending from each face thereof, a pair of separated substantially hemispherical members having circular recesses therein to receive the cylindrical projections from said disc member to form a pivot about which said receptacle may rotate, said hemispherical members cooperating with said disc member to form substantially a sphere, spring means cooperating with said flared portion to maintain said hemispherical members assembled with said disc member and said sphere in its flared seat.

5. In a writing instrument holder of the character described including a base having a bore and a writing instrument receptacle, means for mounting the receptacle from the base comprising a disc connected with the receptacle, a pair of partially spherical members at opposite sides of the disc, means to pivotally connect said partially spherical members with the disc so as to enable relative movement of the instrument holder with respect to the partially spherical members, extensions on the partially spherical members extending into the bore with the spherical surfaces of said members resting on the outer peripheral portion of the bore, and means to draw said extensions down into the bore to retain the same assembled with the base and to clamp the disc between the partially spherical members.

6. In a device of the character described, a base having a bore provided with a flared outer end, a writing instrument receptacle, means for mounting the receptacle from the base for substantially universal movement comprising, a disc carried by the receptacle, a pair of substantially hemispherical members disposed one on each side of the disc to form with the disc substantially a sphere, means to form a pivotal connection between the disc and said substantially hemispherical members, an extension on each of said hemispherical members received in said bore, and resilient means to draw the extensions into the bore to retain the spherical surfaces of the hemispherical members in engagement with the flared end of the bore and thereby force the hemispherical members into snug contact with the opposite sides of the disc.

JOHN W. FITZ GERALD.
